CLAIM

The ornamental design for a cherry tomatoes-shaped container, as shown and described.

DESCRIPTION

FIG. 1 is an isometric view of a cherry tomatoes-shaped container of the applicant's design;

FIG. 2 is a view of FIG. 1 with the top section flipped open thereof;

FIG. 3 is a top view of FIG. 1;

FIG. 4 is a bottom view of FIG. 1;

FIG. 5 is a back view of FIG. 1;

FIG. 6 is a front view of FIG. 1;

FIG. 7 is a right side view of FIG. 1; and,

FIG. 8 is a left side view of FIG. 1.

The broken lines in FIG. 4 are included for the purpose of illustrating a portion of the bottom that forms no part of the claimed design.
